(57) **CLAIM**

We claim the ornamental design for a bicycle crank arm, as shown and described.

DESCRIPTION

FIG. 1 is a front perspective view of a bicycle crank arm showing our new design;

FIG. 2 is a rear perspective view of the bicycle crank arm shown in FIG. 1;

FIG. 3 is a top view of the bicycle crank arm shown in FIG. 1;

FIG. 4 is a rear view of the bicycle crank arm shown in FIG. 1;

FIG. 5 is first side view of the bicycle crank arm shown in FIG. 1;

FIG. 6 is a second side view of the bicycle crank arm shown in FIG. 1;

FIG. 7 is a third side view of the bicycle crank arm shown in FIG. 1; and,

FIG. 8 is a fourth side view of the bicycle crank arm shown in FIG. 1.

In the drawings the broken lines depict portions of the bicycle crank arm that form no part of the claimed design.
